UNITED STATES PATENT OFFICE

117,547

DESIGN FOR TEXTILE FABRIC

Curt E. Forstmann, Montclair, N. J.

Application August 11, 1939, Serial No. 86,617

Term of patent 3½ years

To all whom it may concern:

Be it known that I, Curt E. Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure is a plan view of a piece of fabric showing the design.

The design consists of parallel diagonal narrow stripes, alternate stripes having a rough appearance resulting from loose curly loops of tightly twisted yarn, the remaining stripes having a felted appearance resulting from a smooth background, the edges of the stripes being irregular.

I claim:

The ornamental design for textile fabric, as shown and described,

CURT E. FORSTMANN.
